UNITED STATES PATENT OFFICE.

WILLIAM JOSEPH RUSSELL, OF WOLVERHAMPTON, ENGLAND.

PUMP OR MOTOR.

Application filed January 10, 1923, Serial No. 611,818, and in Great Britain January 13, 1922.

This invention relates to pumps for liquid and to motors operated by liquid under head or pressure, both of the type employing two or more buckets or pistons or the like, hereinafter referred to as pistons, and particularly to the type wherein the liquid flows continuously at substantially uniform velocity.

In the case of a pump, the said pistons are operated through mechanism from a rotating shaft or part and, in the case of a motor, the shaft is operated by the pistons through mechanism so as to rotate.

The construction may be taken to be similar for either pumps or motors but reversed in action; it will therefore only be necessary to describe the construction of an apparatus suitable for a pump; merely adding that, in the case of a motor, mechanically operated valves for liquid are preferable.

According to the invention the rotating shaft or part is provided with a cam of appropriate shape which actuates two or more bell crank levers which are preferably provided with anti-friction devices, such as rollers, where they engage with the cam; the levers are pivoted at substantially equal distances from the axis of rotation of the cam and the pivots are substantially symmetrically arranged with respect to the axis of rotation of the cam. This means that, when there are two bell cranks, a straight line drawn through the axes of their pivots passes through, or approximately through, the axis of rotation of the cam.

To impart uniform velocity to the water, the bucket or piston in contact therewith must move with uniform velocity. Assuming that the shaft to which the cam is attached is rotating at a uniform rate, the cam is so designed that, during that part of the rotation of the shaft which corresponds with the power stroke of the piston, for small equal movement of the shaft and cam, the piston is caused to move through equal longitudinal distances, thus giving equal volumetric displacements and therefore uniform velocity to the water. Thus, if the power stroke of the piston corresponds with, say, 110° revolution of the shaft and cam and it is required that the piston shall move through x units of distance, then for every 1° rotation of the shaft and cam the piston must move $\frac{x}{110}$ units of distance and the cam must be designed accordingly.

Such a cam can easily be graphically laid out by a competent designer.

By similarly forming those parts of the levers which are in contact with the cam, as for instance by fitting rollers of equal diameter and at equal distances from the pivots in the same direction with relation to the direction of rotation, it is assured that the cam operates the levers successively at equal intervals of time and imparts equal motion to the levers, thus fulfilling the purpose of this invention.

Now according to the positions of the pivots and the lengths and direction of those arms of the levers which are in operative connection with the pistons, it is possible to impart equal or proportional motion to the pistons, and the latter may be arranged co-axial with, or parallel or inclined to one another, but all being controlled from the same cam so as to give substantially equal volumetric rates of displacement for corresponding movements of the levers.

The invention is illustrated in the accompanying drawings, Figures 1 to 8, each figure representing, in section, a pump or part of a pump.

In Fig. 1, the pivots 1^a and 1^b are shown as being on a line 1^a , 2 , 1^b , which passes through the axis of rotation 2 of the cam 3 and are at substantially equal distances from this axis.

The arms 4^a and 4^b of the respective bell cranks have rollers 5^a and 5^b which roll on the cam and are kept in contact therewith by suitable means such as by springs (not here shown) tending to force 5^a and 5^b towards one another.

The arms 6^a and 6^b operate, respectively, through links 8^a , 8^b , rods 7^a and 7^b which in turn operate the respective pistons; and since the pistons are co-axial, rod 7^b is tubular in order that the rod 7^a may pass through it.

As the cam 3 rotates, the ends of the bell-cranks which carry the rollers are moved outwards and inwards to follow the profile of the cam, and it will be seen that, if the corresponding arms of the bell cranks are equal in length and the rollers are equal in diameter, then the right hand end of arms 6^a and 6^b will have exactly equal motion, but that movement of the one will occur half a revolution of the cam earlier or later than that of the other.

The downward strokes of the pistons are

caused by their weight aided by the aforesaid springs.

Gland 9^b is required when the level of delivery is above the level of the upper end of the pump cylinder.

By suitably shaping the cam, it may be arranged that the greater part of the upward strokes of the respective pistons occurs at substantially uniform velocity and that the 10 respective periods of uniform velocity overlap.

Fig. 2 shows pump rods 7^a, 7^b which are flexible, as for instance ropes or chains, and are connected with the respective arms 6^a, 6^b by means of arcs in well-known manner. The downward strokes may be caused solely by the weight of the pistons, in which case the cam would be so shaped as to give the pistons suitable downward acceleration. In 20 the case shown, however, springs give part of the downward acceleration, 10^a serving this purpose for the lower piston and 10^b for the upper piston. The working barrel 11 may be held by its own weight against the 25 lifting tendency of the said springs, or it may be anchored. In the former case a tight joint is made at 12 and, when the barrel requires inspection, it may be lifted together with the pistons by hauling the flexible rods 7^a and 7^b.

Fig. 3 shows a pump, particularly suitable for low lift, in which the arms 6^a, 6^b extend in opposite directions so that the pistons are more easily inspected than in the 35 previous constructions. Since the lateral movement of the outer ends of arms 6^a and 6^b is generally relatively small as compared with the length of rods 7^a and 7^b, the links 8^a, 8^b, together with the guides for the upper ends of the rods, may be eliminated.

Fig. 4 shows a compact form of pump having co-axial pump rods in compression. Fig. 5 is an enlarged view of the cam and levers and the connections of the latter with the pump rods. It will be noted that the links 8^a and 8^b are of very simple form, not requiring pin joints, and that the bell cranks, being constantly pressed against the cam, can merely be slotted to receive the 50 pivots 1^a, 1^b, thus greatly facilitating dismounting and assemblage. Springs 10^a, and 10^b produce the return strokes and take up wear.

Fig. 6 shows the application of the invention to a wing pump with oscillating pistons. The pistons may be rectangular and oscillate about the pivots 1^a, 1^b respectively. As here shown, they perform the functions of the arms 6^a, 6^b of the other forms herein described, so that links and rods 8^a, 8^b, 7^a, 7^b are eliminated.

In Fig. 7 the pistons 13^a, 13^b are shown as integral with the arms 6^a, 6^b, respectively, and oscillate about the pivots 1^a and 1^b, which serve to guide the pistons and pre-

vent the weight of the pistons causing friction against the surface of the working barrel. The barrel has open ends, piston 13^a may be pulled out directly and piston 13^b may be pulled out after disconnection of link 14^b.

Fig. 8 illustrates a pump suitable for gritty water. It also shows a case in which the arms 6^a and 6^b are of different lengths, equal displacement of liquid by the two pistons 13^a, 13^b being obtained by making the pistons of area inversely proportional to the length of the arms. Inflated pneumatic tubes 14^a, 14^b permit the necessary strokes, so that the pump rods 7^a, 7^b can be 75 operated directly by the arms 6^a, 6^b, additional inflated pneumatic tubes 15^a, 15^b serving to prevent leakage past the pump rods.

Three or more bell cranks may be used 80 where a multiplicity of pistons is an advantage.

Having thus described the nature of the 85 said invention and the best means I know of carrying the same into practical effect, I claim:—

1. Apparatus for forcing or raising liquid and for producing power from liquid under pressure, comprising reciprocating pistons operating in series, a driving shaft, a cam mounted on the said shaft, bell crank levers 90 engaging the said cam and having their engaging arms similar to each other, pivots on which the said levers turn, the said pivots being disposed equidistant from the axis of rotation of the said shaft and symmetrically with respect to the said axis, and an operative connection between the said bell crank levers and the said pistons respectively, the profile of the said cam being such that, during that part of the rotation of the shaft 95 which corresponds to the power stroke of the piston, for small equal movement of the shaft and cam the piston is moved through equal longitudinal distances, thus giving equal volumetric displacements and therefore uniform velocity to the liquid.

2. Apparatus for forcing or raising liquid and for producing power from liquid under pressure, comprising two reciprocating pistons operating in series, a driving shaft, 115 a cam mounted on the said shaft, two bell crank levers engaging the said cam and having their engaging arms similar to each other, pivots on which the said levers turn, the said pivots being disposed equidistant from the axis of rotation of the said shaft and in the same straight line through the said axis, an operative connection between the said bell crank levers and the said pistons respectively, the profile of the said cam 120 being such that, during that part of the rotation of the shaft which corresponds to the power stroke of the piston, for small equal movement of the shaft and cam the piston is moved through equal longitudinal distances, 125

thus giving equal volumetric displacements and therefore uniform velocity to the liquid.

3. Apparatus for forcing or raising liquid and for producing power from liquid under pressure, comprising two reciprocating pistons coaxial with each other and operating in series, a driving shaft, a cam mounted on the said shaft, bell crank levers, each having one arm engaged with the said cam and the other arm in operative connection with the said pistons respectively, the said other arms being similar and similarly directed to each other, pivots on which the said levers turn, the said pivots being disposed equidistant from the axis of rotation of the said shaft and in the same straight line through the said axis, the profile of the said cam being such that, during that part of the rotation of the shaft which corresponds to the power stroke of the piston, for small equal movement of the shaft and cam the piston is moved through equal longitudinal distances, thus giving equal volumetric displacements and therefore uniform velocity to the liquid.
- 10 4. Apparatus for forcing or raising liquid and for producing power from liquid under pressure, comprising two reciprocating pistons operating in series, a driving shaft, a cam mounted on the said shaft, bell crank levers, each having one arm engaged with the said cam and the other arm in operative connection with the said pistons respectively, the said other arms being different and directed differently from each other, pivots on which the said levers turn, the said pivots being disposed equidistant from the axis of rotation of the said shaft and in the same straight line through the said axis and the profile of the said cam being such that, during that part of the rotation of the shaft which corresponds to the power stroke of the piston, for small equal movement of the shaft and cam the piston is moved through equal longitudinal distances, thus giving equal volumetric displacements and therefore uniform velocity to the liquid.
- 15 5. Apparatus for forcing or raising liquid and for producing power from liquid under pressure, comprising two reciprocating pistons operating in series, a driving shaft, a cam mounted on the said shaft, two bell crank levers each having one arm engaged with the said cam and having the other arm shaped as a piston, the two pistons operating in series, pivots on which the said levers turn, the said pivots being disposed equidistant to the axis of the said shaft and in the same straight line through the said axis and the profile of the said cam being such that, during that part of the rotation of the shaft which corresponds to the power stroke of the piston, for small equal movement of the shaft and cam the piston is moved through equal longitudinal distances, thus giving equal volumetric displacements and therefore uniform velocity to the liquid.
- 20 6. Apparatus for forcing or raising liquid and for producing power from liquid under pressure comprising a driving shaft, a cam mounted on the said shaft, two bell crank levers each having one arm engaging with the cam and having the other arm shaped as a piston, the two pistons operating in series, pivots on which the said levers turn, the said pivots being disposed equidistant to the axis of the said shaft and in the same straight line through the said axis and the profile of the said cam being such that, during that part of the rotation of the shaft which corresponds to the power stroke of the piston, for small equal movement of the shaft and cam the piston is moved through equal longitudinal distances, thus giving equal volumetric displacements and therefore uniform velocity to the liquid.
- 25 7. Apparatus for forcing or raising liquid and for producing power from liquid under pressure, comprising reciprocating pistons of unequal area and operating in series, a driving shaft, a cam mounted on the said shaft, bell crank levers each having one arm engaging the said cam and the other arms of the said levers being of unequal length, these lengths being in inverse proportion to the areas of the said pistons, pivots on which the said levers turn, the said pivots being disposed equidistant from the axis of rotation of the said shaft and symmetrically with respect to the said axis, an operative connection between those arms of the levers which do not engage the cam and the piston in the sense that the piston of smaller area is connected with the longer arm, the profile of the said cam being such that, during that part of the rotation of the shaft which corresponds to the power stroke of the piston, for small equal movement of the shaft and cam the piston is moved through equal longitudinal distances, thus giving equal volumetric displacements and therefore uniform velocity to the liquid.
- 30 8. Apparatus for forcing or raising liquid and for producing power from liquid under pressure, comprising two reciprocating pistons operating in series, a driving shaft, a cam mounted on the said shaft, two bell crank levers each having one arm engaged with the said cam and the other arm in operative connection with one of the said pistons, a slot in each of the said levers, pivots constituting the fulcrums of the said levers respectively, the said pivots engaging in the said slots respectively and being disposed equidistant from the axis of rotation of the said shaft and in the same straight line

through the said axis, the said operative connections between the bell crank levers and the said pistons being maintained by pressure of the latter and the profile of the said cam being such that, during that part 65 of the rotation of the shaft which corresponds to the power stroke of the piston, for small equal movement of the shaft and cam the piston is moved through equal longitudinal distances, thus giving equal volumetric 70 displacements and therefore uniform velocity to the liquid.

9. Apparatus for forcing or raising liquid and for producing power from liquid under pressure comprising a driving shaft, a cam mounted on the said shaft, two bell crank levers each having one arm engaging with the cam and having the other arm shaped as a piston, the two pistons operating in series, pivots on which the said levers turn, the said pivots being disposed equidistant to the axis of the said shaft and in the same straight line through the said axis and the profile of the said cam being such that, during that part of the rotation of the shaft which corresponds to the power stroke of the piston, for small equal movement of the shaft and cam the piston is moved through equal longitudinal distances, thus giving equal volumetric displacements and therefore uniform velocity to the liquid.

10. Apparatus for forcing or raising liquid and for producing power from liquid under pressure, comprising reciprocating pistons of unequal area and operating in series, a driving shaft, a cam mounted on the said shaft, two bell crank levers each having one arm engaging the said cam and the other arms of the said levers being of unequal length, these lengths being in inverse proportion to the areas of the said pistons, pivots on which the said levers turn, the said pivots being disposed equidistant from the axis of rotation of the said shaft and symmetrically with respect to the said axis, an operative connection between those arms of the levers which do not engage the cam and the piston in the sense that the piston of smaller area is connected with the longer arm, the profile of the said cam being such that, during that part of the rotation of the shaft which corresponds to the power stroke of the piston, for small equal movement of the shaft and cam the piston is moved through equal longitudinal distances, thus giving equal volumetric displacements and therefore uniform velocity to the liquid.

In testimony whereof I have signed my name to this specification.

WILLIAM JOSEPH RUSSELL.
